(57) **CLAIM**

The ornamental design for a jewelry case as shown and described.

DESCRIPTION

FIG. 1 is a top perspective view of a jewelry case, showing my new design;

FIG. 2 is a bottom perspective view thereof;

FIG. 3 is a front side view thereof;

FIG. 4 is a left view thereof;

FIG. 5 is a right side view thereof;

FIG. 6 is a rear view thereof;

FIG. 7 is top side view thereof;

FIG. 8 is a bottom view thereof;

FIG. 9 is a top front perspective view of a jewelry case with the cover removed;

FIG. 10 is a bottom rear perspective view of the jewelry case with the cover removed;

FIG. 11 is a front side view of the jewelry case with the cover removed;

FIG. 12 is a left view of the jewelry case with the cover removed;

FIG. 13 is a right side view of the jewelry case with the cover removed;

FIG. 14 is a rear view of the jewelry case with the cover removed;

FIG. 15 is top side view of the jewelry case with the cover removed;

FIG. 16 is a bottom view of the jewelry case with the cover removed;

FIG. 17 is a top front perspective view of a jewelry case with the cover removed, in an opened position;

FIG. 18 is a bottom rear perspective view of the jewelry case with the cover removed;

FIG. 19 is a top front perspective view of a jewelry case with the cover removed, in an opened position and with a ring cover door open;

FIG. 20 is a left side view of the case of FIG. 17; and,

FIG. 21 is a right side view of the case of FIG. 17.

(Continued)

The broken lines in the figures illustrate portions of the jewelry case that form no part of the claimed design.

1 Claim, 14 Drawing Sheets
